GEORGE E. MOLYNEUX, OF BAYONNE, NEW JERSEY, ASSIGNOR TO THE SINGER MANUFACTURING COMPANY, A CORPORATION OF NEW JERSEY.

FEEDING MECHANISM FOR SEWING-MACHINES.

1,355,242.

Specification of Letters Patent. Patented Oct. 12, 1920.

Application filed April 5, 1913. Serial No. 759,043.

To all whom it may concern:

Be it known that I, GEORGE E. MOLYNEUX, a citizen of the United States, residing at Bayonne, in the county of Hudson and State of New Jersey, have invented certain new and useful Improvements in Feeding Mechanisms for Sewing-Machines, of which the following is a specification, reference being had therein to the accompanying drawings.

My invention relates to a feeding mechanism for sewing machines and more particularly to the construction of the feed-dog and throat-plate and will be understood by reference to the accompanying drawings, in which Figure 1 is a side elevation of a machine having my improved feeding mechanism, parts being broken away; Fig. 2 a top view of the throat-plate and feed-dog; Fig. 3 a longitudinal section on the plane of the line 3—3 of Fig. 2; Fig. 4 a transverse section on the plane of the line 4—4 of Fig. 2; Fig. 5 a perspective of the adjustable feed-way guides of the throat-plate; Fig. 6 a perspective view of the three feeding surfaces; Fig. 7 a perspective view of the support for the feed surfaces, and Fig. 8 a similar view of one of the laterally movable feed surfaces. Similar reference numerals indicate similar parts in the several views.

Referring to the drawings, the numeral 1 designates the arm of the machine, 2 the cylinder-bed, 3 the needle-bar, 4 the presser-foot bar, 4' the presser-foot lifter, and 5 the power-shaft. These parts are all of usual and well known construction.

My improved feed-dog comprises a shank 6 secured to the carrier 7 by a screw passing through an elongated slot 8 in said shank to provide for proper adjustment on the carrier. The shank 6 is formed with a T-head 9 having a lengthwise undercut slot 10 adapted to receive the relatively movable members having the feeding surfaces and to hold them against longitudinal movement independently of the shank. The portions of the feed-dog provided with the feeding surfaces comprise the two outer sections 11 and 12, and an intermediate shorter section 14, the latter being back of the needles, and all disposed symmetrically with reference to the center line of the throat-plate. As shown in Fig. 6 each of the sections is mounted upon a base 13 corresponding in form to the undercut slot 10 and adapted to

be assembled therein by insertion at one end of the slot. The spaced toothed blocks of intermediate section 14 are integral with their base, or the parts may be made separate and rigidly secured together. To permit the outside sections 11 and 12 to be swung laterally of the line of stitching they are pivoted on their bases each by means of a pivot screw 15 tapped into the under side of one end of the section.

The throat-plate 16 is formed with two apertures 17 and 18, starting from a plane in front of the needle holes, and converging toward each other in the direction of the line of stitching or away from the operator. The end walls of these apertures, as shown in Figs. 3 and 5, are formed with shoulders upon which are adapted to be seated the projecting ends of the pivoted feed-way guides 19 and 20, these guides having a through opening adapted to receive the outer sections 11 and 12 of the feed-dog. The inner ends of the feed-way guides 19 and 20, or the ends toward the operator, are pivotally secured by screws 21 to the end walls of the apertures, and the outer ends of said guide-ways are pivotally secured, by means of screws 22, to the outer ends of toggle-arms 23, said arms being pivotally connected at their inner ends to a rod 24, which rod at its other end is connected to one arm of a bellcrank-lever 25. The other arm of said lever has a connection 26 to a suitable treadle and is held in its normal position by a spring 27. In such normal position the guides 19 and 20 will rest against the outer walls of the apertures 17 and 18, respectively, thereby holding the outer ends of the feed-dog sections 11 and 12 the maximum distance apart.

The carrier 7 is connected through feed-lever 28 to a bellcrank 29 which receives its motion from an eccentric on the main-shaft 5 to give to the feed-dog its stitch-length or feeding movement. The feed-lift is given by an eccentric 30 on the forward end of said shaft.

The degree of convergence of the apertures 17 and 18, and of the extent of movement of the guides 19 and 20 and the feed-dog sections 11 and 12, may be varied to suit the character of the work, the object of the invention in its present embodiment being primarily to automatically lap two pieces of goods being stitched. In the operation of

a machine having the described feed-dog, the timing of the feed is the same as usual, that is, the feed-dog rises as the needle rises, and moves lengthwise of the stitching when the 5 needle is out of the work. The two pieces of goods to be stitched are abutted as they enter the machine, but before a given section reaches the needles the two pieces are acted upon by the outside feeding surfaces or sections 10 11 and 12, so that when the latter are given their stitch length movement the two pieces will be lapped because of the convergence of said sections in the direction of the line of stitching. Should it be desired 15 with certain goods to produce an amount of overlap greater than that provided with the sections 11 and 12 in their normal position, the operator, by depressing the treadle is enabled to swing the feed-way guides 19 and 20 20 on their pivots, and by reason of the pivotal supports of the feed sections 11 and 12 the latter will be moved by the feed-way guides when the latter are moved, to bring the outer ends of the feed sections closer together, thereby increasing the amount of 25 overlap of the goods.

While I have described and shown my invention in connection with a machine having a cylindrical arm, it is to be understood 30 that it may be used with a flat bed machine, and that any known form of means for giving the feed-dog its movement may be employed.

Having thus set forth the nature of the 35 invention, what I claim herein is:—

1. In a feeding mechanism for sewing machines, a supporting element, two feeding sections mounted thereon for bodily movements transversely of the line of feed, 40 means for imparting operative movements to said supporting element, means for bodily reciprocating said feeding sections transversely of the line of feed, and means whereby the length of said reciprocating 45 movements may be varied at will during the operation of the machine.

2. In a feeding mechanism for sewing machines, a carrier, two feeding sections supported by said carrier for sliding and 50 turning movements relative thereto, and means for imparting operative movements to said carrier.

3. A feeding mechanism for sewing machines comprising, in combination, a pair 55 of reciprocating feeding sections mounted for feeding movements along substantially straight paths arranged at an angle to one another and means for simultaneously varying the paths of feeding movements of said sections.

4. A feeding mechanism for sewing machines comprising, in combination, a feed-bar, a supporting base movably mounted on 60 said feed-bar, a feed-dog section movably mounted on said base, a guide having a sur-

face disposed at an angle to the line of stitching and adapted to guide said feed-dog section, and means for varying the angular relation of said guide to the line of stitching.

5. In feeding mechanism for sewing machines, a feed-dog comprising two pivoted feeding sections inclined relatively to each other in the direction of the line of stitching, and means for varying the angle of inclination of said sections relative to each other, said means being operable during the feeding movement of the feed-dog.

6. In feeding mechanism for sewing machines, a feed-dog comprising two feeding 80 sections converging toward each other in the direction of the line of stitching, and means under the control of the operator for varying the angle of convergence.

7. In feeding mechanism for sewing machines, a feed-dog comprising two pivoted feeding sections, and a support for said sections having a transverse slot adapted to receive and hold them against longitudinal movement independently of the support.

8. In feeding mechanism for sewing machines, a feed-dog comprising two pivoted feeding sections symmetrically disposed with respect to the center line of the throat-plate and converging toward each other in the direction of the line of stitching, the pivots of said section being in advance of the needle holes, and means for moving the free ends of said sections toward or away from each other.

9. In feeding mechanism for sewing machines, a feed-dog comprising two pivoted converging feeding sections the pivots being in a plane in front of the needle hole in the throat-plate, and means under the 105 control of the operator for moving the free ends of said sections toward or away from each other.

10. In feeding mechanism for sewing machines, a feed-dog comprising two pivoted feeding sections, pivoted guides for said sections in which the sections have their stitch length feeding movement, and means for moving the free ends of said guides toward or away from each other to impart a corresponding movement to the feeding sections.

11. In feeding mechanism for sewing machines, a feed-dog comprising two pivoted sections, pivoted guides for said sections, a 120 shift-lever under the control of the operator, and link connections between said lever and the free ends of said guides whereby the latter and the feeding sections may be moved toward or away from each other by the operation of the shift-lever.

12. In feeding mechanism for sewing machines, a feed-dog comprising two pivoted sections, pivoted guides for said sections, a toggle connecting the free ends of said 130

- guides, and a lever under the control of the operator for operating said toggle to move the free ends of the guides and feeding sections toward or away from each other.
- 5 13. In feeding mechanism for sewing machines, a feed-dog comprising a central fixed section at the rear of the needle hole, and two pivoted sections extending on opposite sides of the needle hole converging toward 10 each other in the direction of the line of stitching.
14. In feeding mechanism for sewing machines, a feed-dog comprising two pivoted feeding sections, having work-engaging surfaces lying substantially in the same plane, means for reciprocating said dog to impart simultaneous feeding movements to said sections, means for moving said sections bodily laterally toward and away from each 20 other during the movements of the feed-dog, and means whereby said sections may be manually shifted about their pivots to vary their angular relationship to the line of feed.
15. A feeding mechanism including, in combination, a feed-bar, two feeding elements arranged side-by-side and freely mounted on said feed-bar for bodily lateral and turning movements relative to said feed-bar, and shiftable guiding means for controlling 25 the amplitude of the bodily lateral movements of said feeding elements, said feeding elements being turned relative to the line of feed only during the shift of said guiding means.
- 30 16. A feeding mechanism including, in combination, a feed-bar, two feeding elements arranged side-by-side and sustained by said feed-bar for lateral movements relative to said feed-bar, guideway supporting means, guideways pivotally mounted on said supporting means and coöoperating with the respective feeding elements for controlling the lateral movements thereof as the feed-bar moves back and forth, and manually 40 controlled means for shifting said guideways angularly about their respective pivots to vary the amplitude of lateral movement of the feeding elements.
- 45 17. The combination with stitch-forming mechanism and feeding mechanism includ-
- ing a feed-bar, feeding teeth arranged on opposite sides of the line of seam formation and in advance of the stitch-forming mechanism, arms pivotally and slidably connected to the feed-bar in rear of the stitch-forming mechanism and projecting forwardly, each of said arms supporting the feeding teeth on its respective side of the line of seam formation, a guideway support, guideways carried by said support for controlling 55 the amplitude of lateral sliding movements of the respective arms as the feed-bar moves back and forth, and means whereby said guideways may be shifted to swing said arms on their pivots and thereby vary the direction of movement of said feeding teeth.
18. In a sewing machine, the combination with stitch-forming mechanism, of feeding mechanism including a pair of four-motion feed-dogs with means for moving 60 them simultaneously in opposite directions laterally of the line of seam formation, and treadle controlled means for varying the amplitude of lateral movement of said dogs without stopping the machine.
- 70 19. In a sewing machine, the combination with stitch-forming mechanism, of a pair of pivotally mounted four-motion feed-dogs disposed in angular relation to the line of seam-formation, and means under the control of the operator for varying at will the angular relation of said dogs relative to the line of seam-formation.
- 75 20. In a sewing machine, the combination with stitch-forming mechanism, of a pair of pivotally mounted four-motion feed-dogs, guides for directing the feeding movements of said feed-dogs and relative to each of which guides its respective feed-dog is maintained in fixed angular relation, and means 80 whereby said guides may be shifted to vary their angular relation to the line of seam-formation.
- In testimony whereof I have signed my name to this specification, in the presence of 95 two subscribing witnesses.
